UNITED STATES PATENT OFFICE.

ALEXIS F. GILLET, OF OMAHA, NEBRASKA, ASSIGNOR TO JUBILEE MANUFACTURING COMPANY, OF OMAHA, NEBRASKA.

WINDSHIELD-CLEANER.

1,345,167.

Specification of Letters Patent. Patented June 29, 1920.

Application filed December 22, 1919. Serial No. 346,689.

To all whom it may concern:

Be it known that I, ALEXIS F. GILLET, a citizen of the United States, residing at Omaha, in the county of Douglas, and State 5 of Nebraska, have invented certain new and useful Improvements in Windshield-Cleaners, of which the following is a specification.

The present invention relates to cleaners for windshields and the like, and has for 10 an object to provide a cleaner of this type which may be easily and quickly attached to and removed from a windshield; which will provide the required pressure of the wipers on the glass or pane of the windshield to 15 remove accumulations of dirt, rain, moisture, frost and snow; which provides an easy means for manual operation; and to provide a cleaner which operates upon both sides of the pane or glass at the same time.

20 Another object of the invention is to provide a cleaner composed of relatively few parts which may be economically pressed or formed from sheet steel, and which is constructed to provide the desired pressure by 25 use of relatively light springs; and to provide a cleaner which when not in use will not be in the way, and will not impair vision through the glass.

The above, and various other objects and 30 advantages of this invention, will in part be described, and in part be understood, from the following detailed description of the present preferred embodiment, the same being illustrated in the accompanying drawings, wherein:

Figure 1 is a side elevation of a wind shield cleaner constructed according to the present invention, and as applied to a wind shield, the latter being shown in section.

40 Fig. 2 is an edge elevation of the cleaner as applied to the windshield, a fragmentary view of the latter being shown.

Fig. 3 is a section taken longitudinally through the cleaner on the line 3—3 of 45 Fig. 1.

Fig. 4 is a similar view taken on the line 4—4 of Fig. 1.

Fig. 5 is a detail end view of one of the wipers employed, and—

50 Fig. 6 is a detail top plan view of the guide of the cleaner.

Referring to the drawings by numerals, and wherein like parts are designated by similar numerals of reference throughout 55 the several views, 10 designates the pane of

a windshield which is incased in a marginal frame 11 in the usual manner. The frame 11, being of usual construction, is substantially cylindrical in cross-section as it is formed tubular.

60

The cleaner comprises a runner or guide 12 of tubular construction and open at one side and provided thereat with flaring edges or flanges 13 adapted to snap or engage over the tubular frame 11 for seating the runner 65 or guide 12 on the frame and allowing the guide to slide upon the frame. The guide 12 is provided with a pair of transversely spaced apart ears 14 preferably stamped up from the body of the runner and perforated 70 to receive therethrough a transverse rod 15. The rod 15 carries a yoke 16 which is adapted to straddle the guide or runner 12 and which is suitably perforated for receiving the end portions of the rod 15 therethrough. 75 The yoke 16 has relatively long arms adapted to extend down at opposite sides of the windshield and is preferably of channel construction and provided at each free end with a pair of outturned lugs 17 forming pivotal supports for levers 18 which are connected between the pairs of lugs by pins 19. Each lever 18 is preferably of channel construction with a circular enlargement 20 at one end forming a cup into which is seated 85 one end of a spring 21 which bears at its other end in the channel, and against the yoke 16 and about the rod 15. The rod 15 not only connects the guide and yoke to each other, but also serves as a guide for the 90 spring 21 to hold it in proper alignment with the end of the lever 18. The other end of the lever is relatively long and is offset inwardly beneath the yoke 16, and is of sufficient length for connection near its free end by a 95 pin 22 with the intermediate portion of a wiper 23. The wiper 23 is pivotally supported on the pin 22 at a point preferably midway between the ends of the wiper so that pressure of spring 21 may be evenly distributed upon opposite ends of the wiper through the intermediate connection described. By this construction the spring 21 may be relatively weak as the distribution of the pressure is such that but a light 105 pressure is required.

80

90

95

100

110

Each lever 18 is so constructed and mounted, and each is provided with a wiper 23, the wipers being arranged opposite each other and adapted to bear evenly and uni-

formly throughout their length against the opposite sides of the pane 10 of the windshield.

Each wiper is preferably of channel construction and provided with a strip 24 of felt, rubber or other suitable material for contact with the pane or glass to clear the same.

The yoke 16 serves as a means to equalize the pressure on the levers 18 and as a ready means for handling the device in sliding the guide or runner 12 along the frame 11. The pins 22 which connect the levers 18 to the wipers are preferably in the form of cotter pins which may be readily detached from the levers to facilitate the positioning and removal of the cleaner with respect to the windshield.

By the arrangement of the levers 18 the required pressure is placed upon the wipers 23 and the springs 21 may be relatively small so that while the required cleaning action is obtained, the device may be freely slid along the frame 11 of the windshield and the device may be easily removed and positioned with respect to the windshield.

All of the parts of the device may be constructed of pressed steel with the exception of the rubbing member or squeegee 24.

It is of course understood that the above specifically described embodiment of this invention may be changed or modified in construction and design without departing from the spirit of the invention, such changes and modifications being restricted only by the scope in the following claims.

What is claimed is:—

1. A windshield cleaner comprising a guide adapted to engage over the edge of a windshield, a yoke carried by the guide, levers mounted on the yoke, springs between the levers and the yoke for urging

the levers against the windshield, and wipers carried by the levers.

2. In a windshield, a runner adapted to engage over the edge of a windshield, a yoke carried by the runner and having arms extending over the opposite sides of the windshield, levers pivoted between their ends to the inner ends of said yoke, wipers carried by the levers beyond the yoke, and springs between the levers and the yoke for urging the wipers against the windshield.

3. In a windshield cleaner, a yoke, a runner carried in the yoke for engagement over the edge of a windshield to hold the yoke thereover, spring pressed levers mounted upon the free ends of the yoke, and wipers detachably and pivotally mounted upon the free ends of the levers.

4. A windshield cleaner comprising a runner adapted to be slidably engaged over the edge of a windshield, a rod carried transversely across the runner, a yoke mounted upon the ends of the rod to project beyond the edge of the windshield, the extremities of the rod projecting beyond the sides of the yoke, levers pivoted to the free ends of the yoke, springs arranged about the extremities of the rod and bearing at their inner ends against the yoke and at their outer ends against the adjacent ends of the levers to urge the opposite ends of the levers toward the windshield, and wipers pivoted intermediate their ends to the free ends of the levers for transmitting pressure from the springs uniformly throughout the lengths of the wipers.

In testimony whereof, I have affixed my signature in presence of two witnesses.

ALEXIS F. GILLET.
